UNITED STATES PATENT OFFICE.

PHILLIPS THOMAS, OF EDGEWOOD, PENNSYLVANIA, ASSIGNOR TO WESTINGHOUSE ELECTRIC & MANUFACTURING COMPANY, A CORPORATION OF PENNSYLVANIA.

GLOW-DISCHARGE APPARATUS AND METHOD OF OPERATING THE SAME.

Application filed November 14, 1922. Serial No. 600,824.

My invention relates to telephone systems and apparatus and more especially to sound-wave translating devices.

In its broad aspect, an important object 5 of my invention is to provide a translating device adapted to effect an interchange of energy between a fluid medium subject to vibratory motion and an electrical circuit carrying vibratory electrical currents.

10 More specifically, an object of my invention is to provide translating means wherein sound waves are faithfully translated into correspondingly modulated electrical energy without impairing the quality, tone and 15 quantity of the translated energy.

Another object of my invention is to provide an improved translating device of the glow-discharge type, wherein the intensity 20 of the response to pressure variations is independent of the frequency of such variations.

Still another object of my invention is to provide a glow-discharge apparatus embodying such design as to eliminate the 25 so-called "ground" tone heretofore present in the operation of most discharge apparatus.

A further object of my invention is to 30 provide means for properly shielding the incoming and outgoing circuits associated with the glow-discharge apparatus, whereby the same may be protected from adjacent transmitting systems.

A still further object of my invention is 35 to provide a means which not only protects the glow-discharge from the undesirable effects of disturbing drafts and currents of air but also tends to accentuate the effects of the higher-frequency pressure variations on 40 the glow discharge, all as will appear more fully hereinafter.

With these and other objects and applications in view, my invention further consists in the nature, the mode of operation, 45 the constructional details and the circuit arrangements hereafter described and claimed and illustrated in the accompanying drawing, wherein:

Figure 1 is a diagrammatic view of circuits and apparatus embodying my invention,

50 Fig. 2 is a greatly enlarged detail view of the main discharge electrodes of Fig. 1, together with a third and fourth electrode and means for shielding the positive column,

Fig. 3 is a greatly enlarged detail view of the negative electrode of Figs. 1 and 2, illustrating the form of the discharge surface of the tip when made of material having a high melting point,

60 Fig. 4 is a similar view but showing the nature of the tip discharge surface when made of material having a low melting point,

Fig. 5 is a detail view showing alternative 65 means for protecting the discharge from undesirable air currents, and

Fig. 6 is a detail view illustrating an arrangement for intensifying the effect of the 70 higher-frequency pressure variations.

In the embodiment of my invention shown in the drawing, a pair of electrodes 1 and 2, having spaced sparking tips 3 and 4, respectively, are connected by conductors 5 and 6 to the positive and negative terminals respectively, of a source of direct current energy (not shown). The negative supply conductor 6 is connected to ground by means of a ground conductor 7.

A resistor 8 is connected in series-circuit 80 relation to one of the supply conductors, say 5, and serves to maintain the currents through the discharge substantially constant during variations in the voltage-current characteristic of the discharge caused 85 by pressure changes, all as hereinafter described. In the particular system employed during experimental work, the energy source had an electro-motive force on the order of 6000 volts and the resistance of the resistor 8 was on the order of a megohm.

When the tips 3 and 4 of the discharge electrodes are separated, say $\frac{1}{16}$ " for a system having the constants just mentioned, a discharge is established between the said 95 tips which differs from the ordinary discharge of the arc type in the following important respects: the tips are relatively cool; there is substantially no vaporization, melting or burning of the same, in comparison with that present in discharges of the arc type, the customary hot spot, characteristic of the ordinary arc, is absent, and the discharge, when formed between electrodes of certain materials, as specified hereinafter, takes place in a relatively steady, smooth and unfluctuating manner. The latter operating characteristic of the glow discharge is of especial importance, inasmuch as fluctuations in the operations of the discharge 100 105 110

may be such as to cause potential or current variations which are comparable in magnitude to the variations caused by sound waves, as will be apparent in the light of the following description.

The glow discharge, which is established between the tips 3 and 4, comprises the following portions arranged in their respective order between the negative tip 4 and the 10 positive tip 3, viz, a cathode glow 9, which is in immediate contact with the negative tip 4, a cathode dark space 11, also known as Crookes' dark space, a negative light 12, which is perceptible to the eye, a Faraday 15 dark space 13 and a positive column 14 which terminates on the tip 3 of the positive electrode 1 and which may be perceptible to the eye, all as illustrated in a greatly magnified detail view in Fig. 2.

20 When the discharge is once established and when the current therethrough is maintained substantially constant, the potential drop thereacross varies with pressure and also with the frequency of the pressure variations in the higher portions of the audible-frequency range. The result of such frequency variations on the sensitivity of the discharge is to cause distortion of the higher notes in the audible-frequency range. After 25 considerable experimental work, it was found that the sensitivity of the portion of the discharge including the positive column 14 varies with the frequency of the impressed pressure variations, whereas, the sensitivity of the Faraday dark space 13 was found to be substantially independent of such frequency changes.

Accordingly, apparatus was arranged 40 which made possible the detection of pressure variations in the Faraday dark space 13. The apparatus comprises a third electrode 15, which is disposed in the discharge at the free end of the positive column 14, a fourth electrode 16, which is disposed in 45 the portion of the Faraday dark space 13, bordering on the cathode glow 12, and a repeater device 17. The third and fourth electrodes 15 and 16 are provided with perforations 18 and 19, respectively, on the order 50 of .014" in diameter and are positioned with the perforations in the path of the discharge. Improved results were obtained by employing third and fourth electrodes made of Advance material for reasons which will 55 appear hereinafter. Advance material being an alloy consisting of approximately forty per cent nickel and sixty per cent copper.

The alternating component of voltage 60 which is established between the third and fourth electrodes 15 and 16, in the presence of pressure variations, may be translated into amplified currents of similar wave form by impressing the same upon the grid and filament elements 21 and 22, respectively,

of the repeater device 17, which includes, in addition, a plate element 23. The third electrode 15, which is disposed immediately adjacent to the positive column 14, is connected to the grid 21 by means of a conductor 24 including, in series-circuit relation therewith, a grid-biasing condenser 25. The condenser 25 has a negligible impedance to currents of sound-wave frequency and may also serve to prevent the so-called "quiet 75 voltage drop" between the third and fourth electrodes 15 and 16 from operating to block the tube 17.

The fourth electrode 16 is connected to the filament 22 of the repeater device 17 by means of a conductor 26. The conductor 26 may be connected to ground by means of a ground conductor 27. A condenser 28, having a low reactance to currents of audible frequency, is included in the conductor 26 between the fourth electrode 16 and the ground wire connection 27 and serves to prevent the conductor 26 and the ground connection 27 from operating to short-circuit a portion of the direct current traversing the discharge. A grid-leak resistor 29 may be included in shunt relation to the grid and filament elements 21 and 22, respectively, in order to control the intensity of the negative charges which are accumulated on the grid 21.

A plate-filament circuit for the tube 17 includes a source 31 of direct-current energy and a high impedance resistance coupling device 32. The potential variations which are established across the resistor device 32, when the glow discharge is subjected to pressure variations as, for instance, those caused by sound waves, may be impressed, by conductors 33 and 34, upon the input 100 elements of an amplifying device (not shown) or other circuit arrangement designed to employ such modulated energy.

During experimental work, it was found 105 that the sensitivity of the glow discharge as a translating device decreased as the diameter of the perforation 18 in the third electrode 15 is increased, and that best results were obtained by employing the perforation 110 having a diameter small in comparison to that of the positive column 14. As shown in Fig. 2, the free end of the positive column 14 extends through the perforation 18 without engaging the walls thereof, forming a 115 small tip portion 35. After long operation, the third electrode 15 becomes slightly heated but does not assume the temperature of the glow discharge. The fourth electrode 16, as previously stated, is positioned just 120 out of contact with the negative light 12, inasmuch as contact therewith will cause its destruction, the temperature of the negative light 12 being far above the melting point of the fourth electrode 16.

130 In the development of my invention, con-

siderable difficulty was experienced in establishing and maintaining a glow discharge between the discharge electrodes. The discharge, when once established, was likely to be very noisy in operation. It was found impossible to establish a glow discharge between electrodes of manganese, iron, nickel, carbon, aluminum and molybdenum, while the discharge which was established between 10 electrodes of tungsten, silver and platinum was exceedingly noisy. Greatly improved results were obtained by employing electrodes of copper, but such electrodes did not effect the elimination of a slight "ground" 15 tone which still persisted during the operation of the discharge. Furthermore, the discharge was subject to intermittent abrupt changes in gradient which completely overshadowed the relatively slight changes effected by the pressure variations of sound 20 waves.

The undesirable operating characteristics just mentioned are believed to be partly caused by the high melting point of the 25 negative tip 4 in the instances just mentioned. When the light discharge has been established for a short time between such electrodes, the discharge-surface of the negative tip 4 is hollowed out, forming a conical 30 surface 36 with relatively fine edges or tips 37, as illustrated in Fig. 3. Since the edges or tips 37, reach a very high degree of heat, they become oxidized, causing an intense 35 ionization in the space between the said edges 37 and the cathode glow 12. The result is a break-down in the impedance of the cathode dark space 11, thereby directly short-circuiting the same and connecting the tips 37 to the cathode glow 12. When such action occurs, the operation of the discharge 40 is naturally disrupted.

This undesirable operating characteristic is overcome by the provision of a cathode tip of relatively low melting material, as, 45 for instance, Advance wire. As previously stated, this substance is an alloy of copper and nickel in the general proportions of 60 to 40. When the glow discharge is established between such electrodes, the effect of 50 the discharge is to cause the negative tip 4 to burn away to a convex point thereby forming a convex surface 38, as illustrated in Fig. 4.

The ionization established in the case of 55 the electrode having the low melting point is distributed with substantial uniformity throughout the entire cathode dark space 11 by reason of the form of the surface of the negative tip 4, thereby avoiding any tendency for a short-circuit between the end 60 of the negative sparking tip 4 and the cathode glow 12 and the resulting interruption in the operation of the discharge.

The so-called "ground tone" is further reduced and the general efficiency of operation

of the discharge is increased by making the negative tip 4 of a material having a low heat conductivity, that is, a material which permits the currents traversing the glow discharge to heat merely the end of the negative 70 sparking tip 4 to such temperature that it becomes a source of ionization. When the tip 4 becomes a source of ionization, as just described, the Faraday dark space 13 lengthens, resulting in more stable operation of the 75 discharge. The particular need for a relatively long Faraday dark space 13 was observed when the tip of the positive column 14 would extend across the Faraday dark space 13 to the negative light 12 in the 80 presence of excessive modulation, thereby disrupting the discharge.

The diameter and the length of the negative tip 4 are so adjusted that, when the proper temperature conditions obtain at the 85 end of the negative tip 4, as just described, the diameter of the negative light 12 is approximately the same as that of the cathode tip 4. A greater amount of current than the value necessary to effect such relation 90 causes loud, high-pitched whistling noises in the operation of the discharge, whereas a lower current causes sibilant hisses. A latitude of approximately ten percent, plus or minus, was found to be permissible, for a 95 circuit having the constants previously mentioned. The dimensions of the negative sparking tip 4 employed in experimental work were .075" in diameter and $\frac{3}{32}$ " in 100 length. The angle of the face 39 of the electrode 2, with respect to the longitudinal axis thereof, was also found to affect the operation of the discharge. Optimum operation of the discharge was obtained with an angle of approximately 30°.

When operating my invention in the circuit of a large transmitting station, it was found necessary to provide shielding means for the several conductors associated with the glow-discharge apparatus. This was 110 accomplished by providing the incoming conductor 5 with a shield 41 grounded by a ground conductor 42 and by providing the outgoing conductors 24 and 26, leading from the third and fourth electrodes 15 and 16, 115 respectively, with shields 43 and 44 grounded by conductors 45 and 46, respectively.

It was then found, however, that the operation of the glow discharge was exceedingly unsteady since the conductors and shields functioned as condensers to periodically extinguish the normal glow discharge. The path traversed by one such discharge comprises the condenser formed between the lead 5 and the shield 41, the ground conductor 42, a portion 47 of the conductor 6 between the ground conductor 7 and the negative electrode 2, the negative electrode 2, the glow discharge and the positive electrode 1. This undesirable condition was overcome 125 130

by inserting a resistor 48 in the positive supply conductor 5 immediately adjacent to the positive electrode 1.

The operation of the discharge was found to be still periodically interrupted, though to less extent than before. The periodic interruption was finally determined to be the result of the capacity effects of the shields 43 and 44 with respect to the outgoing conductors 24 and 26 of the third and fourth electrodes 15 and 16, respectively. The discharge circuit for the condenser formed between the third electrode conductor 24 and the shield 43 extends from the shield 43 through the ground connection 45, the ground connection 7, the portion 47 of the negative supply conductor 6, the negative electrode 2 and the space between the negative electrode 2 and the third electrode 15 and the third electrode 15 to the conductor 24. In the case of the fourth electrode conductor 26, a somewhat similar circuit is formed which extends from the shield 44 through the ground connection 46, the ground connection 7, the portion 47 of the conductor 6, the negative electrode 2, the space between the negative electrode 2 and the fourth electrode 16 and the fourth electrode 16 to the outgoing conductor 26.

The condenser effect of the shields 43 and 44 is overcome by inserting a resistor 49 in the portion 47 between the ground connection 7 and the negative electrode 2. The resistance of both stabilizing resistors 48 and 49 may be on the order of 100,000 ohms or thereabouts.

Further improved results may be obtained by minimizing the effect of the positive column 14 upon the characteristic variations of the glow discharge in the presence of pressure variations, as caused by sound waves or drafts of air. In Figs. 1 and 5 is shown one particular means for producing the above mentioned effect comprising a tubular member 51 of insulating material which is supported from one end by the positive electrode 1 and which carries the third electrode 15 from the other end thereof.

The use of copper for the third electrode 15 has the disadvantage that, during the periods when the discharge is not in operation, copper carbonate is formed around the perforation 18 contained therein. When the discharge is established, the particles of copper carbonate are broken away from the third electrode 15 and drop into the positive column inclosure formed by the tubular member 51, causing the discharge to become noisy in operation.

Such shielding means, as just described, while affording protection for the positive column portion 14 of the glow discharge, leaves the remaining portions thereof exposed to the disturbing effects of drafts of

air. Furthermore, finely divided particles of dust in the air, as iron sulphide, were found to interfere with the normal operation of the discharge. Accordingly, an enclosing member 52 was constructed, as shown in Fig. 1. The structure comprises a casing 53 of cylindrical shape having open ends 54 and 55. The discharge electrodes 1 and 2 are carried by said casing 53, with the sparking tips 3 and 4 and apparatus directly associated therewith disposed therein. The open ends 54 and 55 of the casing are closed by reticulate members 56 and 57, respectively, as, for instance, pongee silk or felt.

When employing such structure in a closed room, it was found advisable to cause the sound waves to enter the chamber formed by the casing 53 from one side thereof only, thereby tending to minimize the distortion caused by the sound waves reflected from the walls of the room. The end of the casing, say 54, facing the origin of the sound waves may be covered by pongee silk 56, whereas the remaining end 55 may be covered with heavy felt 57. The heavy felt 57 also serves to prevent the reflection of the sound waves within the casing 53 itself.

The electrodes 1 and 2 are preferably vertically positioned within the casing 53, with the negative electrode 2 uppermost. Such arrangement was found to render the operation of the discharge more steady. The reason for this is thought to be due to the fact that, when the negative electrode 2 is disposed directly beneath the positive electrode 1, travel of the electrons emanating from the negative tip 4 to the positive tip 3 is greatly aided by the upper movement of the air currents caused by the heating of the air in the lower portions of the chamber formed by the casing 53. As can be seen, such effect does not obtain with the negative electrode 2 uppermost.

In Fig. 5 is shown an alternative structure for protecting the glow discharge from the effects of air currents and comprises a shielding tubular member 58 covering the cathode dark space 11 and the negative light 12 and carrying the fourth electrode 16, the result being substantially like that effected by the tubular structure 51 associated with the positive electrode 1. It will be noted that the structure shown in Fig. 5 provides no protection for the Faraday dark space 13 but this space, however, is substantially unaffected by drafts of air tending to extinguish the discharge.

In Fig. 6 is shown a holder 59 of the double-horn type for the discharge electrodes 1 and 2, the same being designed to amplify the effects of the pressure variations in the higher portions of the audible-frequency range to a greater extent than in the lower portions. The arrangement comprises a cylindrical casing 61 forming oppositely ex-

tending horn-like chambers 62 and 63, the larger ends 64 and 65 thereof being exposed and the smaller ends 66 and 67 thereof being interconnected respectively, to form a common portion 68. The electrodes 1 and 2, which are carried by the casing 61, have their discharge tips disposed in spaced relation in said portion 68. By making the resonant frequency of the horn-like chambers 62 and 63 well up in the audible-frequency range, the effects of the higher-frequency-pressure variations are accentuated. In operation, it was observed that the horn would partially convert simple pressure changes at the glow discharge to actual vibrational air currents, thereby increasing the original effect of the pressure variations. The exposed ends 64 and 65 of the horn-like chambers may be covered by felt or other recticulate material 69.

In order to insure that the discharge will be a glow discharge and will continue to be a glow discharge and not change into an arc, I find that the source of potential must be high and that a current limiting device must be used. In addition to the specific dimensions already stated herein, the following actual constructions are noted. In one specific embodiment of my invention, I employed a source of somewhat more than 4000 volts with a resistance in series between it and the discharge device of approximately one megohm. In another specific embodiment of this invention, I employed a source of 4200 volts, together with a current limiting device which restricted the current to one milliampere. The current limiting device used in this instance was a saturation tube.

40 A characteristic difference between the glow discharge and the arc is found in the relation of current to voltage. In the arc the current is much greater and the voltage much smaller than in the glow discharge. 45 Another characteristic difference is that with the glow discharge the electrodes are relatively cool, never becoming incandescent, while with an arc the electrodes are hot and the cathode is usually more incandescent than 50 any portion of the arc itself.

An application of structure just described is in the translation of sound waves produced by a telephone receiver back into modulated currents through the medium of the 55 glow-discharge apparatus, since the effect of the telephone system on modulated currents, especially when transmitted over long distances, is to decrease the intensity of the higher-frequency currents, while the effect 60 of the double-horn arrangement is to accentuate such frequencies.

While I have described my invention as embodying a circuit arrangement having certain specific values, and while I have shown 65 certain embodiments of my invention, it is

apparent that various changes and modifications may be made therein without departing from the spirit of my invention. I desire, therefore, that only such limitations shall be imposed thereon as are indicated by the appended claims or demanded by the prior art.

I claim as my invention:

1. In combination, a pair of spaced electrodes, means for establishing a glow discharge therebetween, said discharge including a Faraday dark space and other portions, and means responsive to variations of an electrical characteristic of said dark space only for delivering corresponding electric currents.

2. The method of effecting a transfer of energy between a fluid medium and an electrical circuit which consists in establishing a glow discharge in said circuit having a Faraday dark space and other portions, subjecting said medium to varying pressures and detecting variations in an electrical characteristic of said Faraday dark space only.

3. A sound-wave translating device comprising a glow-discharge apparatus in a medium responsive to pressure variations due to sound waves, means responsive only to changes in a characteristic of the Faraday dark space resulting from pressure variations in said medium for delivering corresponding electric currents and means for minimizing the effect of the positive column upon the characteristic of the discharge in the presence of sound-wave disturbances.

4. A translating system comprising a pair of spaced discharge electrodes, means for establishing therebetween a glow discharge, said discharge comprising a Faraday dark space, a pair of spaced electrodes positioned in said Faraday dark space, said last-mentioned pair of electrodes having perforations disposed substantially in alignment with each other and with said electrodes and a repeater device for detecting variation in the voltage-current characteristic of the portion of said discharge between said last-mentioned pair of electrodes.

5. A translating system comprising a pair of spaced discharge electrodes, means for establishing therebetween a glow discharge, said discharge comprising a Faraday dark space, a second pair of spaced electrodes positioned in said Faraday dark space, and a repeater device having input conductors connected respectively to said last-mentioned pair of electrodes, one of said conductors being grounded and including a capacitance between the ground connection and its co-operating electrode, said capacitance having a low reactance to currents of audible frequencies.

6. In combination, a pair of spaced discharge elements constituting the positive

- 6
- and negative terminals of a glow discharge device, means for grounding the negative terminal, a pair of spaced electrodes interposed between said discharge elements, a 5 repeater device having input elements, conductors operatively associating said input elements to said spaced electrodes respectively, means for grounding one of said conductors and a capacitance reactance included in said grounded conductor between the ground connection and its co-operating electrode.
7. In an electrical system, a pair of spaced electrodes constituting the positive and negative terminals of a discharge device, supply conductors for said electrodes, means for grounding the negative supply conductor, a third electrode positioned intermediate said pair of electrodes, an outgoing conductor 10 for said third electrode, means for shielding predetermined portions of the several conductors and means included in said negative supply conductor between the ground connection and the negative electrode for preventing the capacity effects between the conductors and the shields from operating to render the discharge unsteady.
8. A translating device comprising a pair of spaced electrodes constituting the positive and negative terminals of a glow-discharge apparatus, the negative terminal being substantially vertically positioned above the positive terminal.
9. In combination, a casing comprising a 15 member having open ends, reticulate members covering said ends, said members being of different degrees of fineness, and a pair of electrodes carried by said casing and having co-operating end portions disposed within said casing in predetermined spaced relation.
10. Discharge apparatus comprising an electrode of copper-nickel alloy having a 20 sufficiently low melting point to prevent the formation of a crater by the discharge. 45
11. In a glow discharge device, a negative electrode comprising Advance wire.
12. The combination with a discharge apparatus, of a pair of electrodes disposed in the discharge, said electrodes comprising an 25 alloy of nickel and copper, having a melting point low relative to its oxidation point.
13. The combination with a discharge apparatus comprising electrodes at the terminals of the discharge, of a pair of electrodes 30 disposed in the discharge, said electrodes comprising an alloy of nickel and copper, in which the copper exceeds the nickel. 55
14. In combination, a pair of spaced electrodes open to the air, means for establishing a glow-discharge therebetween, said discharge including a Faraday dark space and other portions, and means responsive to variations of an electrical characteristic of said dark space only for delivering corresponding electric currents. 60
15. In a discharge apparatus, a pair of terminals exposed to atmosphere pressure, means for maintaining a discharge between said terminals, an additional electrode situated within said discharge and an output circuit associated with said additional electrode, said additional electrode being composed of an alloy of nickel and copper. 70
16. In a discharge apparatus, a pair of 20 terminals exposed to atmosphere pressure, means for maintaining a discharge between said terminals, a pair of additional electrodes situated within said discharge and an output circuit associated with said additional electrodes. 80
- In testimony whereof, I have hereunto subscribed my name this 10th day of November 1922.

PHILLIPS THOMAS.
